UNITED STATES PATENT OFFICE

2,118,738

DEVICE FOR HOLDING CUT PHOTOGRAPHIC FILMS FOR DEVELOPING AND FIXING

John C. Rieger, Louisville, Ky.

Application June 4, 1937, Serial No. 146,331

1 Claim. (Cl. 95—100)

My invention relates particularly to racks or devices for holding individual cut photographic films in the process of developing and fixing. And some of the objects of my invention are,—
 5 first, to provide a rack for holding cut photographic films, of such a character as can be made integral by a moulding process; second, to devise a holding rack for developing and fixing portrait films, so smooth in all parts that, when inserted
 10 into, or removed from, the bath-tank it will not catch into, nor disturb other film-racks that may, at the same time, be hanging in the bath-tank; and third; to design and develop a device for holding cut photographic films for developing
 15 and fixing, that will have no metallic parts to fog the film, installed therein and will have all surfaces in the holding rack rounded to prevent adhesion wherever the installed film would come in contact with the holder.

20 With the above and other objects in view, which will appear in the process of the description, I will explain that my invention, the new and useful device for holding cut photographic films for developing and fixing, illustrated in the accompanying drawing which forms a part of this specification, is a practical device embodying the said novel means and other new and useful details of construction, arrangement and combination of parts, all of which together with 25 their functions, will be described in detail with reference to said drawing and will be definitely pointed out in the claim that follows this description, so that any person skilled in the art, may understand how to construct and use this device.

30 In said drawing, Fig. I is an elevational view of the side of the device for holding cut photographic films for developing and fixing.

Fig. II is a plan view of the underside of the 35 bottom part of said device, showing the drain-holes therein.

Fig. III is a vertical projection, in detail, of the top of an enlarged fragment of parts of said device including a part of the throat.

40 Fig. IV is a cross-sectional view of the channeled sides and bottom of said device for holding cut portrait films, cut in the plane B B.

45 Fig. V is an elevational view, in detail, of a fragment of the inside of an upper portion of the right channeled side of said device, including a cross-section of the horizontal hanger-beam and a cross-sectional view of the two bevelled throat-beams, cut in the plane A A.

This invention has been designed and developed in its various details, not only for the

desirable purpose of affording a photographer a safe and efficient holder for developing and fixing his cut photographic films without the danger of fogging them with metallic contacts such as frequently happens in the use of metallic 5 film-holders, but, also, for the purpose of providing an operator with a film-holder, so smooth in its structure that when moved it will not catch against nor entangle other contiguous or adjacent, similar film-holders that may be hanging 10 beside it. And with these purposes and special objects in view, I will now describe my invention at length, pointing out specifically the new and useful features and explaining the construction and purposes of the individual parts and the 15 combinations thereof, as illustrated in the drawing hereinabove described, in which similar characters refer to similar parts throughout the several views.

In the design and construction of my new 20 device for holding cut photographic films for developing and fixing, I have developed a strong, rectangular, symmetrically-formed film-holder, having a horizontal bottom-portion 2 and extending upward from the ends thereof two 25 parallel side-portions, 1, 1, integral with the bottom-portion; the side-portions, 1, 1, being integrally connected across their upper ends by means of a hanger-beam 4 set parallel with said bottom-portion of said holder. A short distance 30 below the hanger-beam 4 and parallel therewith, I have designed two parallel throat-beams, 3, 3, integrally connecting said side-portions and forming between said beams, the uniform, open 35 throat 3a.

Now, between the ends of the bottom-portion 2 I have made the open channel 2a, provided with convexly-rounded sides and a plurality of drain-holes, 2b, 2b, leading vertically down from the bottom of said channel and adapted to drain 40 out any liquid that may tend to lodge in said channel, as shown in Figs. I, II, and IV. And along the entire length of the side-portions, 1, 1, I have made similar channels, 1a, 1a, provided with similar rounded sides with dimensions similar 45 to the dimensions of the channel 2a, and adapted to join the channel 2a at the lower corners of said film-holder, so that I have, along the inside of both side-portions, 1, 1, and the bottom-portion 2, a continuous channel of like dimensions and character, with the open throat 3a at either end thereof merging directly into said channel. And to prevent undue side-movement 50 of my film-holder while pendent on the suspension rods of the bath tank, or elsewhere, I have 55

provided a notch 4a in each end-portion of the hanger-beam 4, as shown in Figs. I and III.

In my business, as photographer, I have been using various types of holders for cut photographic films for developing and fixing; and I have found them heretofore made of metal and provided with metallic spring-clips or rotating parts, adapted to clasp and hold the film in place after it has been set into its holder. And I have found some objections to film-holders of this character, as follows:—These accessory spring-clips and rotary clasps are tedious to attach to the films or to detach therefrom and, further, these accessory parts are likely to become entangled with other holders that may be hanging with them, provided with similar parts, to the annoyance of the operator who, of course, has to develop his films in an absolutely dark room. Moreover, those parts of the film that rest against metallic contacts in the development thereof become more or less foggy to the detriment of the prints therefrom.

But in the use of my new film-holder, we meet with no metallic parts at all; and we have no accessory clips nor rotary parts to adjust. We select the size of my new film-holder adapted for the size of our film to be developed and fixed; and merely push the film into the top of the two channels, 1a, 1a, and slide it down through the open throat 3a and down along the channels, 1a, 1a, between the two side-portions, 1, 1, until it rests in the bottom of the channel 2a of the bottom-portion 2. We then lift the film-holder by the hanger-beam 4 and place it on suspension rods. The film is now securely held in place in the film-holder by means of the channels, 1a, 1a, in the side-portions, 1, 1, the bottom-portion 2 and the throat-beams, 3, 3, until it is ready for removal from the bath-tank, which is properly done in lifting the holder up by the hanger-beam, allowing the adhering liquid to flow down into the channel 2a, from which it drains out through the waste-holes, 2b, 2b, in the bottom-portion 2 of the film-holder.

But, it should be understood that the specific detail of the portions of my new film-holder which I have herein illustrated and described, should not be considered as limitations in my practical device for holding cut photographic films for developing and fixing, and that, while keeping within the scope of my invention and

claim, any desired modification of these details may be made to facilitate production or economize in fabrication of the portions thereof, provided we keep within the spirit of said invention.

Now, having thus described the various features of my invention, the detail of construction, arrangement and combination of its parts, as well as its functions and purposes; those features and combinations of my invention that I consider new in the structure and useful in the nature of efficiency, convenience and economy in the general practice of photography, and on which I desire Letters Patent granted to me, I have herein below set forth specifically in the following claim:—

In a device of a non-metallic, plastic material, for holding cut photographic films for developing and fixing,—a strong, rectangular, symmetrically-formed film-holder; a horizontally disposed bottom-member therein, smooth all along both outer sides thereof and provided with ample facilities for the efficient drainage of any fluids therefrom; an integral side-member of similar shape smooth on both sides, extending upward a predetermined distance at right angles from each end of said bottom-member in the same plane therewith; a hanger-beam smooth on both sides arranged parallel with said bottom-member and integrally connected flush with the backsides of said side-members at the upper ends thereof; a continuous unbroken channel along the insides of said bottom-member and said side-members, open along the inside thereof; full, smooth convexly-rounded inner sides along the entire length of said channel; convexly-rounded bevels along the upper inside edge of said hanger-beam and the inner edges of the tops of said channels, for the easy entrance of a photographic film therein; a short distance below said hanger-beam and parallel therewith, a pair of smooth, parallel throat-beams extending across from one side-member to the other and integrally-connected therewith, flush with outsides thereof, to prevent snagging adjacent films and film-holders in a developing tank; and full, smooth convexly-rounded bevels along the insides of both said throat-beams, merging in convexly-rounded bevels into said channel in said side-members; as described.

JOHN C. RIEGER. 50
